UNITED STATES PATENT OFFICE.

EDWARD E. WHITMORE, OF CHICAGO, ILLINOIS, ASSIGNOR TO THE CURTAIN SUPPLY COMPANY, OF NEWARK, NEW JERSEY, A CORPORATION OF NEW JERSEY.

CURTAIN-ROLLER.

1,076,728.

Specification of Letters Patent.

Patented Oct. 28, 1913.

Application filed March 15, 1909. Serial No. 483,419.

To all whom it may concern:

Be it known that I, EDWARD E. WHITMORE, a citizen of the United States, residing at Chicago, in the county of Cook and

5 State of Illinois, have invented certain new and useful Improvements in Curtain-Rollers, of which the following is a specification.

This invention relates to curtain rollers 10 of the well known Hartshorn type, and has for its chief object to provide a longitudinally adjustable or extensible roller of superior construction and efficiency in a variety of ways as compared with the standard roller of this type now in use.

At present the longitudinal adjustment or extensibility of these rollers is secured by forming the same in two hollow metallic roller sections provided with registering 20 longitudinal grooves to receive the upper edge of the curtain and a fastening wire, the longer of the sections being equipped internally with the usual tension spring, and the shorter with a connector in the 25 form of a wooden plug fixedly secured in the open end of the shorter section and adapted to interiorly telescope the open end of the longer section, said plug being provided with a longitudinal groove or channel 30 that provides clearance for the inwardly bent metal forming the curtain-holding groove or channel of the metallic sections. Owing to the fact that the wooden plug constituting the telescoping connection between 35 the two metallic sections is liable, through either swelling or shrinkage, to form a poor fit with the open end of the longer metallic section, this form of connector has in many instances proved unsatisfactory. Where the 40 wooden connector shrinks, the telescoping fit becomes unduly loose, permitting the sections to drop apart, as well as destroying the perfect axial alinement of the two sections which should exist to prevent wrinkling of the curtain rolled thereon. Also, the loose fit allows more or less relative 45 turning movement between the two sections, which throws the sections of the curtain-receiving groove or channel out of true alinement. Where the plug swells, it is 50 difficult to effect the connection of the parts without first sufficiently turning down or otherwise reducing the diameter of the wooden telescoping member; where the latter 55 swells when telescopically engaged, it

sticks and renders longitudinal adjustment of the curtain roller sections difficult. To remedy these defects, as well as to provide a generally stronger and more satisfactory roller, I have devised the roller forming the 60 subject-matter of the present invention, and have illustrated an approved mechanical embodiment of the latter in the accompanying drawings, wherein—

Figure 1 is a top plan view of the complete roller, showing the two sections fully closed. Fig. 2 is an enlarged view of the same, partially broken out and broken away between its ends, showing the telescoping parts slightly separated. Fig. 3 is a perspective detail of the shorter section, more particularly illustrating my novel connecting member. Fig. 4 is an enlarged cross-sectional view on the line 4—4 of Fig. 1, also indicating in dotted lines a portion of the 75 curtain wound around the roller.

Referring to the drawing, 5 designates the longer and 6 the shorter cylindrical section of the roller, made of tin or other suitable sheet metal rolled or otherwise shaped up 80 into cylindrical form; said sections being provided with inwardly bent hollow ribs 5^a and 6^a that form longitudinal grooves or channels in which is secured the upper transverse edge of the curtain by means of a 85 wire 7 (Fig. 4) in a manner commonly practised and well understood. The section 6 is closed at its outer end by the usual disk 8 provided with a pintle 9, while the longer section 5 is likewise provided with a centrally apertured end disk 10 through which projects the squared end of the usual spring-actuated and pawl-held mandrel 11, all as well understood in spring curtain rollers of 90 this type.

Referring now more particularly to that feature constituting the novel subject-matter of the present invention, 12 designates a longitudinally split metal connector, consisting, as herein shown, of a piece of sheet metal, preferably of like material to that forming the roller itself, rolled or otherwise shaped up into cylindrical form in cross-section, with the two longitudinal edges thereof spaced sufficiently to form a slot 13, which slot is of just sufficient width to form a way for the passage of the inwardly bent hollow rib 5^a of the section 5. This metallic connector 12 is preferably strongly secured 100 at one end, as by soldering or otherwise, in 105

the open end of the shorter section 6, as shown at 14, while its projecting portion is adapted to interiorly telescope the open end of the longer section 5. Obviously, however, it is immaterial which roller section carries the connector, and the latter might have a sliding fit with both sections within the purview of the invention, in which case the longitudinal slot 13 would extend from end to end of the connector and engage the internal ribs of both. In order to maintain the substantial continuity of the curtain-holding groove or channel, I may also equip the connector 12 with an internally projecting rib 12^a lying inwardly of the slot 13, which rib may conveniently be formed integral with one margin of the slot and extend across and beneath the other, as shown in Figs. 3 and 4. I have found in practice that where the connector 12 is accurately bent or rolled to a truly circular cross-section, it affords a snug and accurate sliding fit with the section 5, not being liable to the variations in its transverse dimension due to atmospheric conditions, as is the case with wooden connectors, and hence yields results much superior in many ways to those afforded by the latter. Preferably, and as herein shown, the connector section 12 is made of a diameter slightly exceeding the internal diameter of the section with which it telescopes, so that, when forced into the latter, the cylindrical walls of the connector are slightly compressed, and the natural resiliency of the metal thus affords a very snug fit which maintains the two sections in perfect axial alinement, even when withdrawn or elongated almost to the point of separation. Where the connector is thus formed, its free end is preferably beveled or tapered, as in-

dicated at 15, which facilitates its entrance into the open end of the section 5. The longitudinal slot 13 of the connector member 12 is made of a width such that, when the connector is operatively engaged with the section which it telescopes the longitudinal margins defining the side slot will snugly embrace the neck of the reentrant rib or ribs of the roller, whereby any relative turning movement of the two sections when united is prevented, and consequently the two curtain-securing grooves or channels 5^a and 6^a are maintained in perfect alinement, which greatly facilitates the threading of the curtain-securing wire 7 therethrough. 55

I claim:

A shade roller comprising tubular sheet metal end members, and a tubular sheet metal connector member, each of the end members having an internal hollow longitudinal bead open longitudinally throughout its outer side and constituting a shade retaining seat, the connector being split longitudinally and provided at one free edge with an internal lip embracing the bead, and the other free edge of the connector overlapping the free edge of the lip and snugly fitting in the angle between the adjacent side of the end member and the bead, said connector having an expanding tendency and thereby maintaining a snug fit within the end members. 65

In testimony that I claim the foregoing as my invention, I have hereunto subscribed my name in the presence of two witnesses. 75

EDWARD E. WHITMORE.
